UNITED STATES PATENT OFFICE.

GUSTAVE M. NELL, OF DENVER, COLORADO, ASSIGNOR TO THE DENVER ROCK DRILL MANUFACTURING COMPANY, OF DENVER, COLORADO, A CORPORATION OF DELAWARE.

ROCK DRILL.

Application filed April 2, 1920. Serial No. 370,820.

To all whom it may concern:

Be it known that I, GUSTAVE M. NELL, a citizen of the United States, residing at Denver, in the county of Denver and State of Colorado, have invented certain new and useful Improvements in Rock Drills, of which the following is a specification.

In rock drilling apparatus of the type having a fluid actuated motor for operating on the drill steel, various means have been provided for blowing out the drill hole by utilizing steel having a bore therethrough and directing the cleansing fluid from the motor to this bore. Occasionally it is desirable to supply an abnormal blast of air to eject accumulated cuttings. The object of the present invention is to provide simple means, whereby the drilling motor may be stopped without cutting off the supply of motive fluid thereto, so that the motive fluid may flow directly to the drill steel.

A further and more specific object is to provide controlling means that can be actuated and held without material resistance and without the necessity of manually actuating and holding the automatic distributing valve.

The accompanying drawing is a diagrammatic view illustrating the improved mechanism.

In said drawing, a cylinder member designated generally by the reference numeral 1 is provided, with the usual chamber 2, in which a piston 3 is mounted to reciprocate, said piston having an extension 4 that has an interlocking engagement with a chuck 5. The chuck 5 is provided in its front end with a socket 6 angular in cross section to receive the rear end of a drill steel, a portion of which is shown at 7. This steel is provided with the usual axial bore 8 for conveying cleansing fluid to the bottom of the drill hole. A tube 8^a extends through the piston and enters the bore 8 for the purpose of delivering water thereto, as is well understood by those skilled in the art. The portion of the tube that enters the bore is of less diameter than said bore, and it will be evident that with the arrangement disclosed, motive fluid from the piston chamber 2 can pass the extension 4 to the bore 8 of the drill steel 7.

Associated with the cylinder member 1 is a valve casing 9 provided with a bore 10, the end portions of which constitute spaced

pressure chambers 11 and 12. The central portion has an annular groove 13, with which communicates a motive fluid supply port 14, and on opposite sides of the groove 14, are annular channels 15, from which extend exhaust ports 16. Distributing and exhaust-permitting passages 17 open into the bore 10 between the central groove 13 and the channels 15, said passages 17 communicating with the piston chamber 2 contiguous to the ends thereof.

An automatic distributing valve is employed that is located in the bore 10, and comprises terminal heads 18 operating in the chambers 11 and 12, and hollow as usual to receive the terminal plugs in the ends of the valve chamber, with an integral shank 19 connecting the heads and having a central flange 20 that is movable with the valve to positions on opposite sides of the central groove 13. It will be observed that when the valve is in its left hand position motive fluid supplied through the port 14, can pass freely into the right hand passageway 17 and into the piston chamber 2 in advance of the piston 3, while the space in rear of said piston is open through the left hand passageway 17 to the atmosphere, through the left hand groove 15 and exhaust port 16. The piston will thus be driven rearwardly. On the other hand, when the piston is in its rear position and the valve is shifted forwardly, then motive fluid supplied through the port 14, will pass through the left hand passageway 17 and enter the piston chamber 2, behind the piston, while the right hand passageway 17 is then open to the right hand exhaust port 16.

For the purpose of effecting the shifting movements of the valve, crossed passageways 21 and 22 are employed that connect intermediate portions of the piston chamber 2 with the pressure chambers 11 and 12. That is to say, the passageway 21 opens into the piston chamber 2 to the left of its center and is in communication with the right hand pressure chamber 11. This passageway 21 is covered by the piston 3 on its rearward movement and is uncovered as it approaches the limit of its forward movement. The passageway 22 which, as shown, is of greater cross sectional area than the passageway 21 opens into the piston chamber to the right of its center and said passageway 22 communicates with the left hand

pressure chamber 12. The passageway 22 is covered by the piston 3 and is uncovered by the front end of said piston as said piston approaches the rearward limit of its movement. It will thus be seen that the motive fluid under pressure which is operating alternately against the opposite ends of the piston 3 has access alternately to the pressure chambers 11 and 12, and consequently against the end faces of the valve.

In addition supplemental ports 23 and 24 open from the distributing passageway 17 into the pressure chambers 11 and 12, respectively, and thus permit a relatively small amount of motive fluid to pass into said chambers whenever the motive fluid has admission to the respective passageways 17. Exhaust ports 25 and 26 open from the pressure chambers 11 and 12, and while of relatively small cross sectional area, are larger than the supplemental ports 23 and 24.

The passageway 22 leading from the piston chamber 2 to the pressure chamber 12, is intersected by a bore 27 in which is located a reciprocating plunger valve 28 that is thus movable to and from a position across the passageway to control the same. The movement of the valve is limited and said valve is retained in the valve casing 9 by a pin 29 engaged in a slot 30 formed in the valve, said valve being provided with an outer actuating head 31 and a coiled spring 32 surrounding the projecting end of the valve and bearing against the head 31 and against the adjacent face of the valve casing 9 to normally hold the valve in open position.

The operation of the mechanism is as follows. Assuming that the piston is starting on its rearward stroke, with the valve in its rear position, motive fluid will enter the front end of the piston chamber 2 and drive the piston rearwardly, and simultaneously, a small amount of fluid is entering the pressure chamber 11 through the supplemental passageway 23 and the pressure in said chamber 11 is sufficient to hold the valve in its left hand position, as illustrated. At the same time, it will be noted that there is but atmospheric pressure in the left hand chamber 12, since this chamber is freely open to atmosphere, and motive fluid under pressure is cut off both through the passageways 22 and 24 until the passageway 22 is uncovered by the piston and the passageway 21 is covered. Motive fluid under substantial full pressure will then pass through the passageway 22 into the left hand pressure chamber 12 and will move the valve to the right. This immediately opens the exhaust from the front end of the piston chamber 2 and completely relieves the pressure in the right hand chamber 11. The valve is now held in its right hand position by the live

fluid passing through the supplemental port 24 into the left hand chamber 12. As shown, the piston has just completed its backward stroke and has passed the passageway 17. It has, as usual, therefore pocketed and highly compressed the air behind it which acts not only as a cushion for the piston, but also reacts to start the piston on its forward stroke.

During the operation of the piston, it will be evident that a portion of the motive fluid will pass along the piston extension 4 and find its way to the bore 8 of the drill steel, thereby effecting a cleaning action. Occasionally, however, it is desired to increase the amount or force of this motive fluid, thus directed to the drill steel. With the present construction, it is only necessary to press the valve 28 inwardly, thereby closing the passageway 22 from the piston chamber to the left hand pressure chamber 12. When this occurs the pressure chamber 12 is cut off from the charge of fluid that effects the shifting of the valve, and consequently the valve will remain in its rear-most position. As a consequence the piston 3 will stop and air under full pressure will pass to the drill steel. The controlling valve 28, it will be noted, when in closed position, has practically no air pressure against it and consequently can be easily held.

From the foregoing, it is thought that the construction, operation and many advantages of the herein described invention will be apparent to those skilled in the art, without further description, and it will be understood that various changes in the size, shape, proportion and minor details of construction, may be resorted to without departing from the spirit or sacrificing any of the advantages of the invention.

Having thus fully described my invention, what I claim as new, and desire to secure by Letters Patent, is:

1. In drilling apparatus, the combination with a cylinder member, a piston therein, and a chuck for holding a steel having a bore, in a position to be operated on by the piston and to receive hole-cleansing fluid from the cylinder, of means for distributing motive fluid to the cylinder member to operate the piston, said means including an automatic distributing valve, means for supplying fluid to the valve for shifting the same, and means for cutting off the fluid supply for shifting the valve while the fluid is admitted to the cylinder member to stop the operation of said valve and hold the piston in position to permit fluid to pass from the cylinder into the bore of said drill steel placed in the chuck.

2. In drilling apparatus, the combination with a cylinder member, a piston therein, and a chuck for holding a steel to be oper-

ated on by the piston and in position to receive hole-cleaning fluid from the cylinder, of means for distributing motive fluid to the cylinder member to operate the piston, said 5 means including an automatic distributing valve, means for supplying fluid to the valve for shifting the same, and means for cutting off the fluid supply for shifting the valve to stop said valve and permit a continuous 10 flow of motive fluid to the cylinder and to a drill steel in the chuck.

3. In drilling apparatus, the combination with a cylinder member, a piston therein, and a chuck for holding a steel to be operated on by the piston and in a position to receive motive fluid from the cylinder to cleanse the drill hole, of a valve chamber and passageways affording communication between the same to the cylinder member, an 15 automatic distributing valve in the valve chamber controlling the passageways, means for effecting the operation of the valve, including a passageway between the cylinder member and the valve chamber controlled by 20 the piston, and a single valve for cutting off fluid through the passageway to stop the valve and hold the piston in a position to 25

permit a continuous flow of fluid under pressure from the cylinder to the bore of the drill steel. 30

4. In drilling apparatus, the combination with a cylinder member, a piston therein, and a chuck for holding a steel to be operated on by the piston, of a valve chamber and passageways affording communication 35 between the same to the cylinder member, an automatic distributing valve in the valve chamber controlling the passageways, means for effecting the operation of the valve, including a passageway between the cylinder member and the valve chamber for supplying motive fluid from the former to the latter to move the valve, and a manually actuated valve for closing the said passageway to stop the operation of the valve and 40 permit the flow of fluid from the valve chamber into the cylinder member and thence to a drill steel placed in the chuck. 45

In testimony whereof, I affix my signature in the presence of two witnesses.

GUSTAVE M. NELL.
